(57) **CLAIM**

The ornamental design of a display for a rack-mounted controller unit, as shown and described herein.

DESCRIPTION

FIG. 1 is a perspective view of a display for a rack-mounted controller unit.

FIG. 2 is another perspective view of a display for a rack-mounted controller unit.

FIG. 3 is a front view of the display for a rack-mounted controller unit of FIG. 1.

FIG. 4 is a left side view of the display for a rack-mounted controller unit of FIG. 1.

FIG. 5 is a right side view of the display for a rack-mounted controller unit of FIG. 1.

FIG. 6 is a top view of the display for a rack-mounted controller unit of FIG. 1.

FIG. 7 is a bottom view of the display for a rack-mounted controller unit of FIG. 1; and,

FIG. 8 is a rear view of the display for a rack-mounted controller unit of FIG. 1.

The broken lines in the Figures are for illustrative purposes only and form no part of the claimed design.
